UNITED STATES PATENT OFFICE.

DOWLING BENJAMIN, OF CAMDEN, NEW JERSEY.

COMPOUND SAFETY-SEAL CONDENSING-CAP.

1,243,132.

Specification of Letters Patent. Patented Oct. 16, 1917.

Application filed November 16, 1915. Serial No. 21,734.

To all whom it may concern:

Be it known that I, DOWLING BENJAMIN, a citizen of the United States, residing at Camden, in the county of Camden and State 5 of New Jersey, have invented certain new and useful improvements in Compound Safety-Seal Condensing-Caps, of which the following is a specification.

My invention relates to improvements in 10 compound safety-seal condensing caps, and more particularly to a cap of the character stated for the radiators of automobiles, the object of the invention being to provide a cap which can be substituted for the ordinary 5 cap in use, and which will compel a circulation of vapor rising from the liquid in the radiator, and during such circulation will condense the vapor and return it to the radiator, thereby preventing loss and maintaining a supply of cold liquid at all times.

In automobile radiators, particularly in cold weather, a certain percentage of alcohol is mixed with the water to prevent freezing and this alcohol renders the fluid very 25 volatile, so that it vaporizes from the heat of the engine. With the ordinary construction of radiator such vapor would escape through the outlet or overflow pipe, whereas with my improvements the vapor would be 30 condensed and returned in liquid form to the radiator.

A further object is to provide a cap of the character stated which permits an escape of steam when the pressure reaches a pre-determined degree, and which also prevents the occurrence of partial vacuum within the 35 radiator.

A further object is to provide a cap of the character stated which permits a circulation 40 of cold air around the same while the automobile is running or standing still, so that the operation of vapor condensation is carried on at all times.

With these and other objects in view, the 45 invention consists in certain novel features of construction and combinations and arrangements of parts as will be more fully hereinafter described and pointed out in the claims.

50 In the accompanying drawings:

Figure 1 is a view partly in elevation and partly in vertical section illustrating my improvements.

Fig. 2 is a top plan view of my improved cap.

Fig. 3 is a view in transverse section on the line 3—3 of Fig. 1.

Fig. 4 is a view in longitudinal section through the cap removed, the section being taken at right angles to Fig. 1.

Fig. 5 is a view in transverse section on the line 5—5 of Fig. 4, and

Fig. 6 is a fragmentary view in elevation illustrating a water seal attachment for the outlet end of the overflow pipe which may be used as a modification in connection with my improved cap.

1 represents a radiator such as commonly employed on automobiles having circulating pipes 2 and 3, and an overflow pipe 4. 70 This overflow pipe performs the function of limiting the water level in the radiator and also permits vapor or steam to escape.

With the construction as ordinarily used, there is a constant loss of liquid not only on account of the escaping vapor, but also because of the splash of the liquid which drops down through the overflow pipe, and which loss is prevented with my improved cap as will now be explained.

The radiator 1 is provided at its top with the ordinary internally screw-threaded collar 5, into which the externally screw-threaded lower end 6 of the cylindrical body portion 7 of my improved cap A is screwed, 75 the downward movement of the cap being limited by a flange 8 as shown.

At the upper closed end of the body portion 7, an annular flange 9 is provided, and this flange 9 is connected by a circular series of bolts 10 with an upper disk 11.

12 is a tubular barrel which communicates at its lower end with an opening 13 in the center of the top of body 7, while the closed upper end 14 of the barrel 12 bears 95 against the under face of disk 11, and the bolts 10 when secured by nuts 15 on their lower ends operate to clamp the barrel securely in place.

Around the outside of the barrel, and spaced therefrom, is a pipe coil 16, the upper end of the coil communicating with an opening 17 in the side of the barrel 12 at its upper end, and the lower end of the coil projecting through an opening 18 in the top 100 of body 7 and terminating at its lower end.

in the form of a restricted nozzle 19 through which the water of condensation drops into the body 7.

The restricted nozzle 19 compels a drop of 5 water to remain at the discharge end of the coil, and by reason of the capillary attraction offers sufficient resistance to prevent any possibility of the vapor passing up the coil, but on the other hand compels the vapor to pass up the column and thence downwardly through the coil and be condensed by reason of the cooling action of the air around the coil.

The air circulates freely around the coil, 15 both transversely and vertically, and to permit a free circulation vertically while the vehicle is at a stand still, I provide openings 20 in disk 11.

In the body portion 7, I preferably locate 20 two baffling disks 21 having openings 22 out of register with each other, and at the lowest portions of the disks, so that while the water is free to flow downwardly, the disks operate as baffles to prevent the splash of 25 the liquid up through the body.

A plug 23 which may be of rubber or any other material is adapted to close the upper end of the overflow pipe 4, and this pipe is connected by a chain 25 with an eye 26 having swiveled connection with a bar 24 secured in the lower end of the body 7, so that when the cap is removed, the plug will be drawn outwardly with the same.

On the outside of the body 7, I provide an 35 outlet spring-pressed check valve 27 closing an outlet port 28 in the body, and on the inside of the body 7, I locate a spring-pressed check valve 29 controlling an inlet port 30. I also preferably provide a liquid inlet spout 40 31 on the body having a cap 32 normally closing the same, and it will be understood that the liquid can be supplied to the radiator through this nozzle 31 without the necessity of removing my improved condensing 45 cap from the radiator.

The operation of my improvements as described is as follows:

The plug 23 prevents any outlet of vapor or liquid from the radiator. Vapor caused 50 by the heat of the engine will rise through the body 7 and barrel 12, and then flow downwardly through the coil 16. During such downward movement through the coil, the vapor will be condensed and will drop 55 from the nozzle end 19 into the body portion 7. By this means I provide a positive circulation of the vapor through the condensing coil, and insure a rapid condensation of vapor as it forms.

60 If an undue pressure occur the valve 27 will open until the excess of vapor or steam has escaped to allow the pressure to fall to normal. If a partial vacuum occur the valve 29 will open, and allow the air to enter to 65 overcome the same.

My improved cap, therefore, operates automatically to maintain a proper quantity of cold liquid in the radiator, preventing loss due to vapor or splash, and insuring a better operation of the radiator.

Instead of using the plug 23 to close the upper end of the overflow pipe 4, I may provide a U-shaped trap 33 secured on the lower end of the overflow pipe 4, and having a flap valve 34 at its open end. The trap 33 75 provides a water seal which prevents the escape of vapor unless the pressure becomes excessive, when the vapor will force out the liquid seal and escape, and form another seal automatically.

The water seal, therefore, operates as a check valve to prevent undue escape of vapor, yet allow the same to escape when it reaches the danger point.

Various slight changes might be made in 85 the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination with a radiator having a water overflow pipe, of means for closing the overflow pipe, a cap in communication with the interior of the radiator and having a condensing member thereon normally closed to the atmosphere but in direct communication with the interior of the radiator, said cap having ports leading therefrom to the atmosphere, and valves automatically operative to normally close said 105 ports, said valves also being operative due to variation of pressure within the radiator to open said ports, substantially as described.

2. The combination with a radiator, of a 110 hollow body in open communication with the radiator, a tubular member having its lower end in communication with said hollow body, said member being free to receive vapor as it passes upwardly through the hollow body, a coil of pipe having its upper end communicating with the upper end of the tubular member to receive vapor therefrom, the lower end of said coil forming a nozzle for discharging the condensed vapor 115 into said hollow body, and automatically operative vent valves communicating with said hollow body to regulate the internal pressure of said body, substantially as described.

3. A radiator cap of the character described, comprising a hollow body for communicating with the radiator, condensing means communicating with said hollow body, and automatically operative vent 120

125 130

valves communicating with the body to regulate the internal pressure of the radiator through the medium of said body, substantially as described.

5. A cap for radiators, comprising a hollow cylindrical body, a tubular barrel closed at its upper end and having its lower end in communication with said cylindrical body, said barrel being free to receive va-

10 por as it passes upwardly through the cylindrical body, a coil of pipe having its upper end communicating with the barrel adjacent its closed end to receive the vapor therefrom, the lower end of said coil forming a

15 discharge nozzle for the condensed vapor, baffle plates located within the cylindrical body portion, said baffles being spaced apart and having openings out of alignment with each other to prevent splash of liquid from

20 the radiator through the cylindrical portion and barrel, substantially as described.

5. A cap for radiators, comprising a hollow cylindrical body, a tubular barrel closed at its upper end and having its lower end in

25 communication with said cylindrical body, said barrel being free to receive vapor as it passes upwardly through the cylindrical body, a coil of pipe having its upper end communicating with the barrel adjacent its

30 closed end to receive the vapor therefrom, the lower end of said coil forming a discharge nozzle for the condensed vapor, substantially as described.

6. A cap of the character described, comprising a body portion, a barrel on top of the body portion communicating with the interior thereof to receive vapor as it passes upwardly through the body portion, and a condensing coil surrounding the outer sur-

40 face of the barrel communicating at its upper end with the upper portion of the barrel, and at its lower end with the body portion, said coil having a restricted nozzle at its lower end inside the body portion, sub-

45 stantially as described.

7. A cap of the character described, comprising a cylindrical body portion having a screw-threaded lower end adapted to engage the screw-threaded collar of a radiator, a

50 barrel communicating with the top of the body portion, a condensing coil around the barrel communicating at its upper end with the barrel, and at its lower end with the body portion, an annular flange around the

55 body portion, a disk above the barrel, and bolts connecting the disk with the flange and clamping the disk against the upper end of the barrel, substantially as described.

8. A cap of the character described, comprising a cylindrical body portion having a

screw-threaded lower end adapted to engage the screw-threaded collar of a radiator, a barrel communicating with the top of the body portion, a condensing coil around the barrel communicating at its upper end with the barrel, and at its lower end with the body portion, an annular flange around the body portion, a disk above the barrel, and bolts connecting the disk with the flange and clamping the disk against the upper end of the barrel, said disk having openings therein for the circulation of air, and said barrel having inlet and outlet valves controlling the pressure in the cap, substantially as described.

9. A cap of the character described, comprising a cylindrical body portion having a screw-threaded lower end adapted to engage the screw-threaded collar of a radiator, a barrel communicating with the top of the body portion, a condensing coil around the barrel communicating at its upper end with the barrel, and at its lower end with the body portion, an annular flange around the body portion, a disk above the barrel, bolts connecting the disk with the flange and clamping the disk against the upper end of the barrel, baffling disks in the cap having openings therein at their lowest portions, and valves controlling the pressure in the body portion, substantially as described.

10. The combination with a radiator having an overflow pipe therein, of means for closing the overflow pipe, a condensing cap on the radiator communicating with the interior thereof, and automatically operative inlet and outlet valves controlling the pressure in the cap, substantially as described.

11. The combination with a radiator having an overflow pipe, of a condensing cap on top of the radiator, a plug closing the inlet end of the overflow pipe, and a flexible device connected to the plug and having swiveled connection with the cap, substantially as described.

12. A cap of the character described, having a cylindrical body portion, a condensing coil above the body portion communicating therewith, a water inlet nozzle on the body portion, a member normally closing the nozzle, and automatically operative valves controlling the pressure within the body portion, substantially as described.

In testimony whereof I have signed my name to this specification in the presence of two subscribing witnesses.

DOWLING BENJAMIN.
